PROCESS IN DIGESTING CELLULOSE

Sjune Svensson, Hissmofors, Sweden

Application October 3, 1935, Serial No. 43,411
In Sweden October 13, 1934

6 Claims. (Cl. 92—7)

In applying the processes for obtaining a circulation of the digesting liquid in digesting cellulose, which processes consist in introducing a gaseous medium by means of an injector, jet apparatus or other introducing means into a conduit opening at the upper and lower part of the digester, the said conduit being at least at its lower part connected to or provided with a screen element or the like, into which conduit the fibrous material in the digester is prevented from entering, and according to which processes the digesting liquid is caused to circulate from below upwardly in the conduit and from above downwardly in the space of the digester filled with fibrous material, it has appeared that a rather long time is required to cause a more extensive circulation and to obtain as uniform a temperature of the digesting liquid as possible already at the beginning of the digestion. The inventor has, thus, found that the injector or jet apparatus does not operate completely effectively until the digesting liquid has reached a temperature of about 70° to 80° C. which causes that an unnecessarily long time is required to obtain the desired temperature equalization of the digesting liquid, which at the beginning of the digestion usually has a temperature of about 35° to 40° C. This will also cause that the time necessary for reaching the final digestion temperature becomes relatively long.

The said drawbacks are removed by the present invention according to which at least at the beginning of the digesting period the digesting liquid introduced into the digester during the circulation is preheated before it reaches the injector.

The accompanying drawing illustrates a cross section of a sulphite cellulose digester provided with a device for applying the process according to the present invention.

In the digester 1 is mounted the circulation conduit 2 the lower part of which being connected to the bottom screen 3 of the digester and the upper part being provided with the screen 4. To the circulation conduit 2 is connected a conduit 5 which is provided with an injector or jet apparatus consisting of the bent pipe 7 and the injector nozzles 8, through which steam or sulphurous gas or steam and sulphurous gas may be introduced into the circulation conduit. Another steam supply pipe 6 is connected to the circulation conduit 2 at a place situated below the junction with the conduit 5.

When the necessary quantity of fibrous ma-

terial and digesting liquid has been introduced into the digester and the digestion is to begin, steam or sulphurous gas or steam and sulphurous gas first are supplied through the conduit 5, and then steam is supplied to the circulation conduit through the pipe 6. The quantity of steam supplied through this pipe is preferably adjusted so that the digesting liquid passing through the pipe up to the injector will obtain an increase of temperature, the near 70° to 80° C. the better, since this is the temperature at which the injector begins to operate effectively. The portion of the tube 6 located in the circulation conduit 2 may be T-formed and provided with perforations, or it may be provided with upwardly directed replaceable nozzles for controlling the steam quantity.

In certain cases it may be suitable to interrupt the steam supply through the tube 6 when the entire digesting liquid has reached the temperature at which the injector operates completely effectively.

Since the injector causes more rapid circulation when the digesting liquid is preheated the advantage is obtained that considerably large heat quantities may be supplied for a short period so that the starting period and consequently also the digesting period become shorter. This is obtained according to the invention without using any expensive devices for preheating the digesting liquid prior to the same being supplied to the digester.

The steam supply pipe 6 need not be connected to the circulation conduit 2. It may also open into the bottom of the digester in the vicinity of, or at the screen 3 since, due to the action of the injector or the jet apparatus, the liquid surrounding the screen 3 is sucked into the circulation conduit and it is, of course, just the liquid surrounding the screen which is heated when steam is introduced into the bottom of the digester.

The distance between the conduits 5 and 6 at the places where they open into the circulation conduit should be so great that the heat supplied will be uniformly distributed before the digesting liquid reaches the injector.

Having now described my invention, what I claim as new and desire to secure by Letters Patent is:

1. In a process of digesting cellulose, in which a gaseous medium is introduced, for example, by means of an injector into a conduit, opening at the upper and lower part of the digester, in

order to cause a circulation of the digesting liquid from below upwardly in the conduit and from above downwardly through the space of the digester filled with fibrous material, and into which conduit the fibrous material is prevented from entering, the conduit being at least at the lower part connected to a screen element, pre-heating the digesting liquid on its way upwards before it reaches the injector, at least at the beginning of the digesting period.

2. In a process as claimed in claim 1, introducing steam as gaseous medium into the conduit.

3. In a process as claimed in claim 1, introduc-

ing sulphurous gas as gaseous medium into the conduit.

4. In a process as claimed in claim 1, introducing steam and sulphurous gas as gaseous medium into the conduit.

5. In a process as claimed in claim 1, pre-heating the digesting liquid by introducing steam into the conduit at a place situated below the injector.

6. In a process as claimed in claim 1, pre-heating the digesting liquid by introducing steam into the lower part of the digester near the screen element.

SJUNE SVENSSON.
